TRIM MOLDING FOR ELECTRONIC EQUIPMENT CABINETS OR SIMILAR ARTICLES

Grant E. Allen, Jr., and Fred Bohm, Atlanta, Ga., assignors to Scientific-Atlanta, Inc., De Kalb County, Ga., a corporation of Georgia

Filed Oct. 23, 1965, Ser. No. 87,862

Term of patent 14 years

(Cl. D13—6)

FIGURE 1 is a perspective view of one end and the outer surface of an indefinite length of a trim molding for electronic equipment cabinets or similar articles, showing our new design; and

FIGURE 2 is a view similar to FIGURE 1 but showing the inner surface of the said molding.

We claim:

The ornamental design for a trim molding for electronic equipment cabinets or similar articles, as shown and described.
